UNITED STATES PATENT OFFICE.

VICTOR F. CARL, OF BROOKLINE, MASSACHUSETTS.

TAGGING-MACHINE.

1,396,406.

Specification of Letters Patent. Patented Nov. 8, 1921.

Application filed November 13, 1919. Serial No. 337,815.

To all whom it may concern:

Be it known that I, VICTOR F. CARL, a citizen of the United States, and resident of Brookline, county of Norfolk, Commonwealth of Massachusetts, have invented an Improvement in Tagging-Machines, of which the following description, in connection with the accompanying drawings, is a specification, like characters on the drawings representing like parts in each of the several views.

This invention relates to apparatus for affixing tags to articles of merchandise such as textile and dry goods in general and includes in its more comprehensive embodiment means for printing distinctive marks such as price or size marks or both on each tag and also means for severing individual tags from a strip of tag stock which may be of paste-board or other suitable material as usual. A principal object of the invention is to provide a machine of the type stated that is capable of rapid and semi-automatic movement for printing, severing and affixing to the article to be tagged, individual tags in a reliable, accurate manner with provision for closing and pressing down the pin points of the tag under the surface of the material in the same way that the tags are commonly affixed by hand but insuring a more complete flattening and securing of the crossed pin points than is attainable in the ordinary hand affixing. A further important advantage in the use of the present apparatus is that it aids in safe-guarding the operator against being pricked by the pin points both in affixing the tags and in handling the tagged merchandise afterward. The foregoing and other objects and advantages of the invention will more fully appear from the following detailed description, and the distinctive features of novelty will be pointed out in the appended claims.

Referring to the drawings:

Figure 1 is a plan view showing the essential working portions of a machine embodying my invention;

Fig. 2 is a side elevation thereof with parts broken away in vertical section and other parts removed;

Fig. 3 is a fragmentary detail on line 3-3 of Fig. 2 showing a one-way driving connection to the operating shaft;

Fig. 4 is a transverse section on line 4-4 of Fig. 2;

Fig. 5 is a transverse section on line 5-5

of Fig. 2, looking in the direction of the arrows;

Fig. 6 is a detail plan view showing certain of the pin bending instrumentalities removed;

Fig. 7 is a sectional detail of the pin bending and flattening head;

Figs. 8, 9 and 10 are diagrammatic elevations showing successive stages in the affixing of the tags and the flattening down of the pins in crossed relation;

Fig. 11 is a bottom plan view showing an illustrative form of printing die or plate;

Fig. 12 is a detail elevation showing the tag holding plate which is removably fixed to the bottom of the tag applying head; and

Fig. 13 is an elevation showing a portion of a strip of tag stock equipped with pins and adapted to be used in the present machine.

10 indicates a suitable table top or support for the operative elements of the apparatus. To this support is fixed a bracket mounting 11 of a length corresponding to the lengthwise extension of the operative elements and having a horizontal extension 11^a overhanging the table and spaced a short distance thereabove sufficient to permit the insertion 80 and handling of the material pieces thereunder. Between this overhanging extension 11^a and the table top is mounted a presser plate 12 under which the material is adapted to be engaged. This presser plate is fixed to the 90 table support at its inner end as indicated at 12^a and its forward portion is recessed as indicated at 12^b to permit the movement of the tag applying head therethrough. The extension 11^a is formed with a vertical 95 slideway 13 adjacent one end thereof in which is fitted for sliding movement a tag applying head 14. This head has a post 15 projecting upwardly therefrom equipped with a laterally extending arm 15^a which 100 is engaged by a nut head 16 adjustably fitted to the upper end of a rod 17 fitted for vertical movement in the support. Thus a downward movement of the rod 17 will press downward the head 14, while a compression 105 coil spring 18 re-acting against the bracket support 11 presses underneath the arm 15^a and tends constantly to hold the head 14 elevated. The lower end of the rod 17 is equipped with a lateral arm 19 bearing a 110 roller 19^a at its extremity and this roller is held by the spring 18 in constant engage-

ment with the periphery of a cam 20 which is fixed on an operating shaft 21 which for present purposes may be considered the prime drive shaft of the machine. The post 15 also constitutes a plunger having a capacity for limited movement with respect to the head 14. For this purpose a compression coil spring 22 is housed in the head 14 and reacts upwardly against a flange 23 borne by 10 the plunger 15 normally holding the plunger with an enlarged head 15^b thereof at an upper limit of movement and so that the bottom of the plunger head 15^b is substantially flush with the top of a tag holding socket 15 15 24 in the bottom of the head 14 as now to be described. This tag holding socket or seat 24 is formed in a plate 25 removably fixed to the bottom of the head 14, this plate being of a U-shape as seen in Fig. 12 so as to permit 20 the tags to be slid thereinto by the feeding device to be described, and being equipped with ledges 24^a at each side of such socket to retain the tag therein with a capability of being yieldingly pressed outward therefrom after the tag is affixed to the material. 25 The intermediate side of this plate 25 at the outer side of the head thus serves as a limiting and positioning stop to determine the position of the tag and locate it in alinement 30 for application to the material. It will be understood that different plates 25 with tag holding sockets of varying sizes according to the dimensions of the tags being handled may be selectively employed. When the 35 head 14 is elevated the tag holding seat 24 is in alinement with a guideway 26 for the tag strip which is carried by the rearward portion of the extension 11^a. To effect the accurate alinement of the socket 24 with this 40 guideway the nut 16 is adjustable on the rod 17 and is preferably equipped with a knurled head 16^a for convenient manipulation. As a further aid to this alinement in case the cam 20 should become worn or not 45 be accurately positioned, I may also employ a nut 27 threaded on the lower portion of the rod 17 and engaging a spacing sleeve 28 on said rod, the top of which sleeve engages the bottom of the table 10. The sleeve 28 50 may be also equipped to actuate the presser plate 12 to lift the same slightly for insertion of the work and for this purpose I show it equipped with a forwardly and upwardly extending finger 29 which engages underneath the plate 12 toward the rear thereof as indicated at 29^a.

The guideway 26 for the tag strip extends to the inner or receiving end of the bracket 11 which has a slot 30 formed lengthwise 60 through the base thereof to receive the penetrating prongs or pins P of the tags and permit them to slide therewith. The top surface of the extension 11^a at each side of the slot 30 has fitted thereto spacing plates 65 31 the dimensions of which may be varied

according to the size of the tags being handled and over these plates a cover plate 32 is fixed, this plate constituting the top retaining surface of the tag guideway 26. The plate 32 has a passage 32^a therethrough 70 to afford clearance for the movement of a printing die 33 which is removably fitted to the bottom of a presser head 34 slidably fitted for vertical movement in ways 34^a of the support. The printing die 33 may have 75 lateral flanges thereof engaged in undercut way in the bottom of the head 34 as indicated at 33^a and it may be locked against displacement by a latch 35 pivoted to the head at 35^a. The head 34 is also equipped 80 with a shear knife 36 which is shown as spaced from the die 33 the length of one tag and is also in position with respect to the head 14 to sever the tag which has been positioned in the socket 24 of the head 14. 85 For actuating the head 34 to sever the tags and to print the same, said head is equipped on its top with a laterally extending bar projection 34^b which is engaged by a pull rod 37, the lower end of which is pivoted at 38 90 to a lever 39 which is pivoted at 40 to a bracket 41 depending from the table. The outer end of the lever arm 39 is equipped with a roller 42 which engages a cam 43 fixed to the shaft 21. The roller 42 is held 95 against this cam with a tendency to move the head 34 upward by a coil spring 44 which reacts against the rod 37 to press the same upward. It will be noted from Fig. 5 that the relation of the cams 43 and 20 on 100 the shaft 21 is such that when said shaft turns in a counter clockwise direction the cam 43 will first act to press the head 34 downward severing the foremost tag which is then in the socket 24 and printing the tag which is second back therefrom just before the head 14 is pressed downward to apply the foremost tag to the material. It will also be noted that by thus printing the second tag back from the tag applying station at each movement, there is allowed an interval of time for the ink of the impression to strike in and dry before the printed tag is engaged by the applying instrumentalities. For moving the tag strip forward in the guideway 26 the resilient presser finger or prong 45 is provided, this member being carried by a lever arm 46 which is pivoted to the frame work at 47. The arm 46 is acted on by a spring 48 to move the finger 45 for feeding movement when permitted by a cam 49 which is secured to the shaft 21. This cam which engages a downward extension 46^a of the lever arm 46 has a contour such as to draw back the finger or prong 45 over the tag strip during the period of actuation of the heads 14 and 34 and it releases the arm 46 for forward operative movement upon the upward retraction of these heads. For the operation of the 110 120 125 130

feeding finger 45 the top plate 32 is cut away as indicated at 50. The end of the feeding finger 45 is preferably bifurcated as indicated at 45^a so as to straddle the backs 5 of the pins on the tags and these bifurcated extremities may be either rubber tipped for better frictional engagement with the tag strip or they may be pointed so as to slightly prick into the tag for feeding engagement.

10 With the mechanism so far described the tags are fed successively into operative position and printed and severed and then pressed down on to the surface of the material that is to receive them. In this operation 15 it will be noted that after the tag is borne down on to the material surface by the head 14, there is a small further movement of the plunger head 15^b occasioned by the yielding of the spring 22 which causes 20 the head 15^b to engage directly upon the looped back of the tag pin to hold it firmly assembled with the tag and the tag pressed securely and immovably upon the material with the spaced apart pin prongs 25 penetrating through the material and projecting underneath the same. For initially bending these pin prongs so as to cross them, oppositely acting slide bars 51, 52 are provided, these being operative in guides 53 underneath the table base 10 and in alinement with the pin prongs as the tag is pressed to the material by the head 14. It will be noted that the table 10 is provided with a slot 53^a through which the pin prongs project 30 so as to be engaged by these slide bars. The slide bars 51, 52 are engaged for actuation by the ends of levers 54, 55, respectively, which are pivoted underneath the table to adjustable pivots 56. The pivots 56 are adjustable 35 so as to insure exactly simultaneous operation of the two slide bars 51, 52 and also to take care of differences in spacing of the pin prongs, and for this purpose these pivots are carried by pivot blocks 57 slidably held underneath the table and adjusted by screws 58. The inner ends of the levers 54, 55 are engaged by slide bars 59 guided underneath the table, and the inner ends of these bars have pins or rollers 60 which 40 are engaged by a cam 61 fixed on a shaft 62 vertically journaled in a bracket 63 fixed to and depending from the table base. The shaft 62 has fixed at its lower end a spiral gear 64 which is driven by a spiral pinion 45 shown as one-half the size of the gear 64 and fixed on the shaft 21. Thus the shaft 62 will be driven at one-half the rate of the shaft 21 and the operating cams 20 and 43 mounted thereon and the came 61 is a double lobed one with the lobes thereof arranged 50 to actuate the bars 51, 52 in the interval between actuations of the head 14 and while said head is pressed down. The pin prongs being thus crossed they are engaged by a 55 pin 66 extending transversely across the end of a hollow plunger 67 which is slidably mounted in a vertical bearing 68 underneath the table. The plunger 67 which is oblong in cross section as will be noted by a comparison of Figs. 2 and 4 has fitted therein 60 a head 69 for limited yielding movement with respect thereto. This head 69 is normally equipped with a notch 70 in its upper end adapted to receive therein the pin 66 so that when the head 69 is pressed upward 65 with respect to the plunger 67 the top face 69^a of said head may become operative. The head 69 is normally held retracted downward with respect to the plunger 67 by compression coil springs 71 housed in the plunger 67 and reacting against a flange 69^b of the head 69. The head 69 is equipped with a depending projection 72 the lower end of which is engaged by the extremity of a lever arm 73 which is pivoted at 74 in a bracket 75 mounting depending from the table base. The lever arm 73 has rigid therewith a rearward and upward extension 73^a which is equipped with a roll 75 that engages a cam 76 fixed on the shaft 21. This cam 76 is so 80 arranged and proportioned that immediately after the bars 51, 52 have crossed the pin prongs, it will elevate the head 69 moving with it the plunger 67. In this movement the transverse pin 66 engages between the 85 crossed prongs and presses them down in opposite directions against the bottom of the material. Then on a further upward movement of the head 69 and after the plunger 67 has been stopped by engagement underneath the material, the face 69^a comes into 90 pressing engagement with the prongs and flattens them down close and secure against the under surface of the material, the pin 66 being then received within the slot 70 and thus not interfering with the complete 95 pressing down of the prongs. Any suitable means may be provided for actuating the shaft 21 but for this purpose I show a disk or drum 77 having a clutch engagement 100 with the shaft 21, this clutch engagement being shown as of the roller type and serving to impart a one-way movement to the shaft 21. The disk 77 is turned for its 105 operative movement by a flexible band 79 which may extend down to be operated by a suitable treadle (not shown). For returning the disk 77 a coil spring 80 is shown anchored to a fixed portion of the frame 110 work. For coöperation with the printing die 33 a suitable inking tape 81 may be provided which is carried on rolls 82, 83 at each side of the mounting and may be fed from one to the other intermittently either 115 by hand or by any suitable automatic device (not shown). The operation of the mechanism having been set forth in connection with the description of the individual features need not be repeated in detail. The strip of tag material M equipped with pins 120 125 130

as seen in Fig. 13 is supplied to the machine in strip form and introduced into the guideway 26 to be fed forward step-by-step by the feeding member 45, each feed movement corresponding to the length of a tag. The material piece to be tagged is introduced under the presser plate 12 which it will be understood is of a yielding character to permit this and upon actuation of the disk 77 through the band connection 79 to the treadle the sequence of operations already described is carried out, the foremost tag being sheared off and directly thereafter moved down upon the material, the pin prongs thereof being pressed through the material. Then while the tag and its pins are held securely in place by the plunger head 15^b, the instrumentalities for bending the pin prongs comprising the bars 51, 52 and the plunger 67 with its contained elements become operative as described and the bending of the pin points down against the surface of the material in crossed relation is completed. For normally holding the plunger 67 downward and so that the roll 75 is kept in engagement with the cam 76, any suitable means may be employed which is shown as a coil spring 74^a having one end engaged with the shaft 74 and its other end anchored to the bearing bracket thereof. Likewise suitable springs 59^a may be provided for holding the bars 59 in constant engagement with the cam 61, *i. e.*, so as to open the bending slides 51, 52 when permitted by the cam. I am aware that the invention may be embodied in other specific forms without departing from the spirit or essential attributes thereof, and I therefore desire the present embodiment to be considered in all respects as illustrative and not restrictive, reference being had to the appended claims rather than to the foregoing description to indicate the scope of the invention.

Having described my invention, what I claim as new and desire to secure by Letters Patent is:

1. A tag affixing machine, comprising means for pressing a tag upon a material piece with the pin prongs projecting through the material, means for preliminarily crossing the pin prongs, and means for pressing the crossed pin prongs closely against the under surface of the material.

2. A tag affixing machine, comprising 55 means for pressing a tag to a material piece with the pin prongs thereof projecting through the material, means for preliminarily bending the pin prongs to cross the same, and a plunger equipped with an element to engage the crossed pin prongs to press them back upon the material and also equipped with another element relatively movable with respect thereto for flattening the pin prongs and pressing them closely 60 against the material.

3. A tag affixing machine, comprising 65 means for preliminarily bending the pin prongs of a tag to cross the same, a hollow plunger having a cross pin to engage the 70 crossed pins and having also a presser head relatively movable with respect thereto for flattening the pin prongs and pressing them closely against the material.

4. A tag affixing machine, comprising a 75 pair of slide bars mounted to act oppositely for preliminarily bending the pin prongs of a tag to cross the same, a plunger having a member to engage the crossed pin prongs to press the same back upon the material, and a presser head relatively movable with respect thereto for engaging the pin prongs to flatten them and press them closely against the material.

5. A tag affixing machine, comprising a 85 guideway for a tag strip, means for severing individual tags, a tag applying head mounted for movement to apply the severed tag to a material piece, and a plunger associated with said head and having movement with 90 respect thereto for engaging the pin head of the tag as it is applied to the material for holding the same secure for a pin bending operation.

6. A tag affixing machine, comprising a 95 tag applying head mounted for movement to apply a tag to a material piece, a plunger associated with said head and movable with respect thereto for engaging the pin head of an applied tag to hold the same firmly for 100 bending, and bending instrumentalities having means for preliminarily crossing the pin prongs of the tag and other means for flattening the crossed pin prongs against the material.

In testimony whereof, I have signed my name to this specification.

VICTOR F. CARL.
